UNITED STATES PATENT OFFICE.

SAMUEL R. BAILEY, OF AMESBURY, MASSACHUSETTS.

SEAT-CUSHION FOR CARRIAGES, &c.

SPECIFICATION forming part of Letters Patent No. 650,806, dated May 29, 1900.

Application filed February 27, 1900. Serial No. 6,734. (No model.)

To all whom it may concern:

Be it known that I, SAMUEL R. BAILEY, a citizen of the United States, residing at No. 188 Main street, Amesbury, in the county of 5 Essex and State of Massachusetts, have invented new and useful Improvements in Seat-Cushions for Carriages and other Vehicles, of which the following is a specification.

This invention relates to improvements in 10 seat-cushions for carriages and other vehicles. It is especially well adapted for spring-cushions having spiral springs interposed between the bottom board and stuffing; and it has for 15 its object to allow the side and rear edges of the cushion to yield properly without causing its springs or filling to be brought in contact with any rigid or unyielding part or inclosing rib on the bottom board of the seat-cushion, which is a common objection to 20 devices of this kind generally in use.

The invention is carried out as follows, reference being had to the accompanying drawings, in which—

Figure 1 represents a top plan of the invention 25 shown as applied to a carriage-seat. Fig. 2 represents a similar view showing the padding or filling of the seat-cushion removed. Fig. 3 represents a cross-section on the line 3 3 shown in Fig. 1 and Fig. 4 represents a 30 cross-section on the line 4 4 shown in Fig. 1.

Similar letters refer to similar parts wherever they occur on the different parts of the drawings.

In the drawings, A represents the seat of a 35 vehicle, having outwardly-flaring back and side portions B B' B' of the box, as usual.

C is the bottom or base board of the seat-cushion, adapted to rest on the carriage-seat A, as is common in devices of this kind.

40 D D D represent the metal spiral springs, attached in their lower ends in any well-known manner to the bottom or base board C of the seat-cushion.

To the bottom or base board C are secured 45 a series of metal stays or braces E E, to the upper ends of which is secured a metal skeleton bar or rail F. The stays or braces E are inclined so as to correspond to the flare or rake of the back and side portions B B' B', 50 as shown.

On top of the springs D D D is located the horsehair or other suitable stuffing or fill-

ing G, the whole being covered with cloth or leather H, which after being stretched over the skeleton bar F is tacked or otherwise secured to the edges of the base or bottom board C, as shown.

Heretofore in devices of this kind a solid inclosing rib, usually made of wood, was secured to the upper portion of the sides and back portions of the base-board C, but such solid rib was objectionable, as it prevented the yielding of the cushion at or near the outer edges of the same and prevented the proper yielding of the springs arranged at or near the outer edge of the cushion and caused the body of the rider to come in contact with such solid inclosing rib. This objection is entirely obviated in my improvement, in which I use instead of a solid cushion-incloser a metal skeleton frame composed of inclined stays or braces E, secured at their lower ends to the base-board C and connected in their upper ends to the metal skeleton rail F, as shown.

This device is particularly well adapted to 75 vehicles having outwardly-flaring box-seats, as it permits the free compression of the entire cushion-seat all around its edge without coming in contact with any rigid ribs or projections usually employed for inclosing the 80 springs or padding.

The invention is very simple and is a great improvement upon old methods of constructing seat-cushions.

What I wish to secure by Letters Patent 85 and claim is—

A vehicle-seat comprising a box having outwardly-flaring back and side portions, a base, a series of outwardly-flaring stays or braces secured to said base and having the flaring 90 portions thereof lying substantially parallel with the said flaring back and sides of the box, a metallic rail secured to the upper ends of said stays or braces, a cushion arranged upon said base within the said rail and stays, and a covering inclosing the cushion, rail and stays, substantially as described.

In testimony whereof I have hereunto set my hand in presence of two subscribing witnesses.

SAMUEL R. BAILEY,

Witnesses:

ALBAN ANDRÉN,
LAÜRITZ N. MÖLLER.
